F. L. SIMON

CONVEYER

Filed July 24, 1923

ପତ୍ର

John W. Darley.

Chorzele

UNITED STATES PATENT OFFICE.

FRED L. SIMON, OF BALTIMORE, MARYLAND.

CONVEYER.

Application filed July 24, 1923. Serial No. 653,588.

To all whom it may concern:

Be it known that I, FRED L. SIMON, a citizen of the United States, residing at Baltimore, in the State of Maryland, have invented certain new and useful Improvements in Conveyers; and I do hereby declare the following to be a full, clear, and exact description of the invention, such as will enable others skilled in the art to which it appertains to make and use the same.

My invention relates to conveyers.

Among the objects of my invention are:—

To provide a portable conveyer which can be moved from place to place for the purpose of stacking goods in tiers.

To provide a portable conveyer comprising carrying fingers which are spaced apart, said fingers being arranged upon endless chains which form the conveying element so that said carriers can be introduced beneath a platform composed of spaced apart loading bars having but a slight elevation from the floor.

By the attainment of this object, I avoid the heretofore necessary operation of lifting the article to be transported to a considerable height so that fingers could be moved thereunder in order to engage said article.

To provide a simple, cheap, light and portable conveyer which can be adapted for the transporting of objects having various shapes by simply changing the shape of the carrier or the platform, or both.

These and further objects of my invention will be set forth in the following specification, reference being had to the accompanying drawings, and the novel means by which said objects are effectuated will be definitely pointed out in the claims.

In carrying out my invention I make use of the instrumentalities illustrated in the accompanying drawing:—

Figure 1 is a side view, partly in section, of a conveyer constructed according to my invention.

Figure 2 is an enlarged view of some of the parts shown in Figure 1 looking in the direction of the arrow 2 in said figure.

Figure 3 is a section along the line 3—3 in Figure 1 looking in the direction of the arrows.

Figure 4 is an enlarged detailed view of parts hereinafter referred to.

In the drawings:—

55. 10 represents a boom which is composed of channel irons such as 11 which extend from

end to end of said boom for the purpose of guiding the conveyer rollers 12. The channel irons 11 are spaced apart and maintained in correct relative position by lattice work such as 13 and near each end of said boom a plate such as 14 is secured. In the plates 14 there are provided bearing for the shafts 15 and 16. The shaft 15 is mounted in housings such as 17 which are supported upon the carriage 18. The carriage 18 is mounted upon a pair of wheels such as 19 and a castor 20. A guide 21 is pivoted as at 22 to the carriage 18 and a slide 23, pivoted at 24 to a plate 25 secured to the boom, slides freely within the guide 21. A hand or power operated winch 26 is mounted upon the guide 21 and connected by a rope to the hook 27 secured to the slide 23. Said winch is for the purpose of raising or lowering the boom 10 in order to deliver the articles to any height desired as hereinafter explained. When the boom 10 is raised to the proper height it is maintained in the said position by the engagement of the pawl 28 with the ratchet wheel 29.

Pivotedly mounted as at 30 upon each side of the carriage 18 near one end thereof are a pair of levers 31, the lower ends of which are pivotally connected to a flange provided at the sides of the supporting plate 32. A nut is swivelled in any approved manner at the upper end of each of the levers 31 and a screw 33 is threaded in said nut. Said screw is revolvably supported by bearings 34 and is revolved by a handle 35. The supporting plate 32 carries a plurality of loading bars 36, each of which is provided with an upturned end 37.

Sprocket wheels 38 and 39 are rigidly mounted upon the shafts 15 and 16. A pulley 40 is mounted upon the shaft 15 and is revolved by the belt 41 which also passes over the pulley 42, the latter being revolved by the electric motor or other source of power 43 through the intermediary of the reduction gearing 44^a. Sprocket chains such as 44 extend the length of the boom 10 and around the wheels 38 and 39. A plurality of shafts such as 45 is secured to said sprocket chains and the rollers 12 are revolvably mounted on the ends of said shafts thus serving to support the chain between the wheels 38 and 39.

At whatever portion of the chains 44 it is desired to attach carrying fingers such as 46, two of the shafts 45 are located close together, a plurality of links 47 is mounted

upon one of said shafts and a similar plurality of links 48 is mounted upon other of said shafts. The upper ends of said links are pivotally connected by the shaft 49 and the fingers 46 are rigidly secured to said shaft. By comparing Figures 2 and 3 it will be noted that the bars 36 are so located that the fingers 46 will pass between same. One of the outermost fingers 46 carries a tappet 50 which is located to strike the cam 51 formed upon the boom 10 for a purpose hereinafter explained.

Any desired plurality of the rollers 12 may be grouped adjacent the fingers 46 in order that the shafts 45 may support the weight of the article 52 that is being transported and a chain such as 53 has one of its ends connected to one of said shafts and the other end connected to one of the fingers 46. Only one tappet 50 and one chain 53 are shown in the drawings but it is to be noted that more can be used if desired. For a purpose hereinafter explained latches such as 54 are revolvably mounted upon the shafts 45 and said latches are arranged to engage pins such as 55 which are mounted in the ends of one of the outside fingers 46. Each latch is provided with a tappet 56 located to be struck by the pin 57 which is secured to the boom 10.

A chute 58 composed of a plurality of bars located similarly to the bars 36 so that the fingers 46 can pass therebetween, is rigidly secured to the arm 59 and the latter is pivoted as at 60 to the boom 10. A brace 61 is pivoted as at 62 to the arm 59 and there is swivelled in the end of the brace 61 the screw 63 which is threaded in the nut 64. The nut 64 is swivelled upon the boom 10 and is turned by the handle 65.

The operation of my improved conveyer is as follows:—

The operator turns the handle 35 so as to move the levers 31 in a clock-wise direction thus lifting the supporting plate 32 from the floor. The carriage 18 can then be wheeled to any position desired.

The operator then applies power to the winch 26 and raises or lowers the boom 10 so as to place the chute 58 in the proper location for the delivery of the articles where desired. The operator then drops the pawl 28 to maintain the boom in said position.

The operator then turns the handle 35 in such a direction as to bring the plate 32 in contact with the floor. He then starts the motor 43 and delivers the articles upon the top of the bars 36 as shown at the left of Figure 1. It is to be noted that in thus delivering the articles the upturned ends 37 locate the articles in correct position to be acted upon by the fingers 46.

As the chains 44 move in a direction of the arrow 5 on the under side of the boom 10

they bring the tappets 56 against the pin 57 thus removing the latch 54 from the pin 55 and allowing the fingers 46 to drop upon the plate 32 between the bars 36. The continued motion of the chains 44 then moves the fingers 46 end-wise between said bars and between the article to be carried and plate 32. As the chains 44 move around the wheel 15, the chain 53 becomes taut and lifts the fingers 46 through the bars 36 into contact with the article and then carries the article on the upper side of the boom 10 until it slides from the conveyer when the chains 44 move around the wheel 39. When the article slides from the conveyer it drops onto the chute 58, and the latter by means of the adjustable brace 61 may be set at any angle to deliver the article where desired.

After the article drops from the conveyer onto the chute 58 the fingers 46 may or may not drop of their own weight, but in any case the tappet 50 comes into contact with the cam 51 and said fingers are moved upwardly until the pin 55 engages the latch 54.

The fingers 46 then move on the under side of the boom 10 in the direction of the arrow 5 until the latch 54 is unlocked and said fingers again engage the plate 32.

Thus it will be seen that I provide a conveyer capable of being readily transported from place to place and capable of piling articles in tiers.

It is further to be noted that by arranging the fingers 46 to have an end-wise movement between the bars 36 it becomes unnecessary to lift the articles to a considerable height from the floor in order to bring them into operative relation with the conveyer as has heretofore been necessary. This improved result I obtained by the end-wise motion of the fingers 46 with reference to the bars 36.

It is to be noted that the winch 26 is merely representative of any means for elevating or depressing the boom 10. The motor 43 and the mechanical connections for revolving the sprocket wheel 15 are representative of any source of power and any form of connection therefrom to said wheel.

While I have shown one form of mechanism for elevating and depressing the plate 32, and one form of mechanism for controlling the operation of the fingers 46, it is to be understood that these mechanisms have been shown and described for illustrative purposes only and in no wise to limit the scope of my invention for many changes may be made therein without departing from the spirit thereof.

I claim:—

1. The combination with a boom, a conveying element thereon and carrying fingers mounted on said element, of fixed loading bars located to mesh with said fingers, and means for introducing said fingers endwise

between said bars to engage the surface of an article placed on said bars.

2. The combination with a boom, a conveying element thereon, and carrying fingers mounted on said element and movable in relation thereto, of fixed loading bars located to mesh with said fingers, and means for introducing said fingers endwise between said bars to engage the surface of an article placed on said bars.

3. The combination with a boom, a conveying element thereon, and carrying fingers mounted on said element, of fixed loading bars located to mesh with said fingers, and means operated during the movement of said element for introducing said fingers endwise between said bars to engage the surface of an article placed on said bars.

4. The combination with a boom, a conveying element thereon, and carrying fingers mounted on said element, of fixed loading bars located to mesh with said fingers and means operated by the movement of said element for introducing said fingers endwise between said bars to engage the surface of an article placed on said bars.

5. The combination with a boom, a conveying element thereon, and carrying fingers mounted on said element, of fixed loading bars located to mesh with said fingers, means for introducing said fingers endwise between said bars to engage the surface of an article placed on said bars and means for afterward moving said fingers transversely to said bars to remove said article from said bars.

6. The combination with a wheeled carriage, a boom mounted on said carriage, a conveying element movably mounted on said boom, and carrying fingers mounted on said element, of a supporting plate mounted on said carriage, of loading bars secured to said plate located to mesh with said fingers, and means for introducing said fingers endwise between said bars to engage the surface of an article placed on said bars.

7. The combination with a wheeled carriage, a boom mounted on said carriage, a conveying element movably mounted on said boom, and carrying fingers mounted on said element, of a supporting plate mounted on said carriage, means for moving said plate in relation to said carriage, of loading bars secured to said plate located to mesh with said fingers, and means for introducing said fingers endwise between said bars to engage the surface of an article placed on said bars.

8. The combination with a boom, a conveying element thereon, and carrying fingers mounted on said element comprising up-

turned ends to locate articles placed thereon, of fixed loading bars located to mesh with said fingers, and means for introducing said fingers endwise between said bars to engage the surface of an article placed on said bars.

9. In a conveyer, the combination with fixed loading bars for supporting articles at a slight distance from a floor, a boom, and a conveying element on said boom, of carrying fingers pivotally mounted on said element, means for introducing said fingers endwise between said bars, means for moving said fingers bodily with said element in order to transport said article, and means for moving said fingers into position for endwise introduction between said bars.

10. In a conveyer, the combination with means for supporting articles at a slight distance from a floor, a boom, and a conveying element on said boom, of carrying fingers pivotally mounted on said element, means for introducing said fingers endwise between said floor and article, means for moving said fingers bodily with said element in order to transport said article, means for moving said fingers into position to be introduced between said floor and article, means for locking said fingers in said position and means for unlocking said fingers.

11. In a conveyer, the combination with fixed loading bars for supporting articles at a slight distance from a floor, a boom, and a conveying element on said boom, of carrying fingers pivotally mounted on said element, means for introducing said fingers endwise between said bars, means for moving said fingers bodily with said element in order to transport said article, a chute for receiving said articles from said fingers, and means for moving said fingers into position for endwise introduction between said bars.

12. In a conveyer, the combination with fixed loading bars for supporting articles at a slight distance from a floor, a boom, and a conveying element on said boom, of carrying fingers pivotally mounted on said element, means for introducing said fingers endwise between said bars, means for moving said fingers bodily with said element in order to transport said article, a chute pivotally mounted on said boom for receiving said articles from said fingers, means for moving said chute with reference to said boom, and means for moving said fingers into position for endwise introduction between said bars.

In testimony whereof I affix my signature.
FRED L. SIMON.
